UNITED STATES PATENT OFFICE.

JOHN BUNYAN WRIGHT, OF GREENSBORO, NORTH CAROLINA.

AIR-BRAK

No. 888,566.

Specification of Letters Patent.

Patented May 26, 1908.

Application filed October 9, 1907. Serial No. 396,652

To all whom it may concern:

Be it known that I, JOHN B. WRIGHT, a citizen of the United States, residing at Greensboro, in the county of Guilford and 5 State of North Carolina, have invented a new and useful Air-Brake, of which the following is a specification.

This invention relates to apparatus of that class employed for automatically operating the brakes of a railway train in case of derailment, or in the event of movement of the truck or trucks to an abnormal position with respect to the body of the car. In devices of 10 this class, as heretofore constructed, it has been usual to employ a separate brake setting device for each of the trucks, and to place in the train pipe a valve or valve connection for each truck, but this has been found to some extent objectionable, owing 15 to the numerous train pipe connections with the consequent increase of danger of leakage and in the matter of expense of applying a separate valve mechanism for each truck.

One of the principal objects of the present 20 invention is to materially lessen the cost of installation and the danger of leakage in the train pipe, by the employment of a single valve in connection with each car, and to provide means whereby said valve may be 25 operated from each of the trucks.

A further object of the invention is to so 30 arrange and construct the mechanism that the valve may be located at any suitable point, either at the center or at the end of the car, or at such other point as may be deemed advisable by the type of car to which the device is applied.

A further object of the invention is to provide a novel form of valve and train pipe 35 connection and to provide a pair of independently operable means, each of which may be moved for the purpose of forcing the valve to open position without affecting the position of the other.

40 A still further object of the invention is to provide a valve structure of such nature as to readily permit cutting off of the valve in case any of the parts are disarranged or broken.

45 A still further object of the invention is to provide means for locking the valve in open position after the operation of either of the valve actuating devices, so that in case the latter should return to normal position after 50 a momentary operation of the valve, the

latter will not be closed and the train pipe pressure will be reduced to an extent sufficient to insure an emergency application of the brakes.

A still further object of the invention is to 60 provide an improved form of truck connection which will insure positive opening movement of the valve in the event of derailment of the truck or in case a truck should jump to a siding as the train is crossing a switch, or in 65 the event of any abnormal movement in any direction of either the truck or the body of the car.

With these and other objects in view, as will more fully hereinafter appear, the invention consists in certain novel features of construction and arrangement of parts, hereinafter fully described, illustrated in the accompanying drawings, and particularly pointed out in the appended claims, it being 75 understood that various changes in the form, proportions, size and minor details of the structure may be made without departing from the spirit or sacrificing any of the advantages of the invention.

80 In the accompanying drawings:—Figure 1 is a side elevation illustrating the application of the invention to an ordinary form of passenger, freight, or flat car. Fig. 2 is a similar view showing the arrangement of the 85 valve at one end of a hopper car. Fig. 3 is a sectional plan view of the valve. Fig. 4 is a transverse sectional view of the same on the line 4—4 of Fig. 3. Fig. 5 is a vertical section of the mechanism arranged at each car, the view being in a direction transverse of the car. Fig. 6 is a sectional plan view on the line 6—6 of Fig. 5. Fig. 7 is a plan view of the cam bar carried by the bolster or other 90 part of each truck.

95 Similar numerals of reference are employed to indicate corresponding parts throughout the several figures of the drawings.

The valve mechanism is arranged within a 100 casing 10 that is carried by a bracket or hanger 11 of any suitable size and shape and arranged to be bolted or otherwise secured to the under side of the car platform, to the sills, or to the end portion of a hopper or similar 105 car, or in any other position most suitable to the type of car on which it is to be employed. At one end of the valve casing is an air entrance chamber 15 that is provided at one end with a threaded nipple 16 for the recep- 110

tion of one end of the train pipe x , and at the opposite end is an externally threaded nipple 17 that is coupled to the section x' of the train pipe. Between the two train pipe sections extends a cylindrical strainer 18 in order to prevent the passage of dirt from the train pipe into the valve casing. This arrangement avoids the necessity of employing a separate T-branch on the train pipe and the continuous flow of air through the pipe is not interfered with, except when the valve mechanism is operated. At a central point in the casing 10 are internal threads for the reception of a valve seat plug 20 that is formed of brass or other similar metal. This plug has a central passage 21 at the inner end of which is a conical seat for a valve 22 that is carried by a stem 23. At the opposite end of the stem is secured a disk 24 that is normally pressed outward by a helical compression spring 25 that surrounds the stem of the valve and is seated in a recess in the outer portion of the plug 20. This spring tends to hold the valve to its seat and the seating operation is assisted by the pressure of air in the train pipe, the whole area of the valve being exposed to train pipe pressure. The passage 21 communicates with a circular chamber 28 from which lead one or more ports 29 to the periphery of the plug, and that portion of the valve casing opposite the chamber 28 is provided with an annular recess 30 from which lead a number of discharge ports 32, so that in case the valve is opened, the air may pass from the train pipe through the port 21, the chamber 28, and thence through ports 29 and 32 to the outer air, reducing the train pipe pressure quickly and to an extent sufficient to result in an emergency application of the brakes.

At a point between the valve and the train pipe connection is located a conical plug valve 34 having at one end a stem 35 for the application of a key or wrench. Should any of the parts of the mechanism become broken or out of order, it is merely necessary to turn this valve in order to cut off the mechanism for that particular car without affecting the mechanisms on the remaining cars of the train.

At the outer end of the casing 10 is an enlarged chamber provided with two diametrically opposed openings in which are fitted bushings 36 of brass or similar metal, these being held in place by small pins or keys 37. Through these bushings pass rock shafts 38 that extend to the actuating mechanism of the trucks. These shafts are wholly independent of each other, and to the head of each is secured a double operating cam 39. The cams for convenience are formed of iron or steel and each is bored for the reception of two plugs 40 and 41 that may be formed of brass or other metal. The plugs are renewable, so that in case of wear it will be a simple

matter to replace them. The two plugs 40 extend from the flat face of the cam and normally occupy a position close to the disk 40. Should either of the cams be turned, say to the position indicated by dotted lines in Fig. 4, one of the plugs 40 will come into contact with the disk and will start the inward movement of the same, and as the cam continues to revolve, the adjacent plug 41 will be brought into engagement with the disk, forcing the latter finally to the dotted line position and opening the valve to a sufficient extent.

It has been found in practice that the cam or cams may be turned but momentarily and will not retain their valve opening position owing to breakage or derangement of the truck connections, and as this in many cases will not result in the desired reduction of train pipe pressure, it has been found desirable to employ means for locking the valve in the open position. For this purpose a pivotally mounted locking pawl 40' is employed, the operating end of the pawl being normally pressed against the periphery of the disk 24 by a spring 41, while the tail 42 of the pawl projects through a suitable opening formed in the valve casing. When the disk 24 is moved inward to a sufficient extent, the pawl 40' will be forced inward by the spring 41' and will engage against the outer face of the disk, thus locking the same from return movement under the influence of the spring and air pressure and holding the valve locked in the open position so as to insure the desired reduction in train pipe pressure and the resultant application of the brakes.

To the under side of the car body at a point adjacent each of the trucks is secured a casing 50 that is provided with a cylindrical bore for the reception of a vertically movable cylindrical stem 51, and to the lower end of this stem is secured a link 52. Each link is of approximately fusiform in contour, tapering slightly toward each end, and the weight of the stem and link is carried by a helical tension spring 53 that extends between two pins 54 carried one by the casing and the other by the stem 51.

One side of the casing 50 is enlarged and is provided with a vertical recess 55 opening into the bore of the casing, and through the walls of the recess extends a cylindrical opening arranged to form a bearing for the reception of one end of the rock shaft 38, and this shaft may be formed of a single member extending from the truck to the valve casing, or it may be formed of a number of sections, especially when it must follow other than a straight line.

Secured to the rock shaft at a point within the recess 55 is a rocker arm 56 having a rounded outer end that fits within a recess 57 in the upper portion of the stem 51. The parts are so adjusted that under normal con-

ditions the weight of the stem and link will not be imposed on the rocker arm 56, while at the same time the flat sides of the rocker arm engaging the vertical walls of the recess 5 57 will serve to prevent any rotative movement of the stem and link. Should the link receive movement in a vertical direction, the arm 56 will be rocked, and the movement will be transmitted through the shaft 38 to 10 one or other of the cams 39.

Projecting from any suitable portion of the truck, as, for instance, from the bolster or one of the transoms, are two horizontally disposed brackets 60 to which are secured two 15 cam plates 61 that are rigidly secured together by a horizontal bar 62. The bar and plates are fastened to each other by rivets or bolts 63 and one of these forms a support for a revolvably adjustable disk 64. The two 20 disks carry crank pins 65 which are connected by parallel bars 66, and the distance between the two bars may be increased or diminished by turning the disks with the rivets or bolts 63 as centers.

Each disk and each cam plate 61 is provided with an arcuate row of openings 68, all of these openings being equi-distant from the center of movement of the disk. These 25 openings are arranged for the passage of a securing bolt 69, held in place by a nut 70. When it is desired to adjust the distance between the bars 66 the bolts are removed and the disks are turned to the desired extent, after which the bolts are inserted through the 30 newly alined openings in the disks and plates and the parts are secured in position. This structure as a whole constitutes an operating cam that coacts with the link 52 to operate the valve. The cam bar is supported by the 35 structure while the link is carried by the body of the car and should there be any abnormal movement of either member with respect to the other, the bar and link will be brought into engagement and the link will be 40 moved vertically, such movement being transmitted in the manner previously described for the purpose of effecting opening movement of the valve.

If the truck is derailed and moves downward, the bar will engage the lower arm of the link and the stem 51 will be pulled downward. Should the truck jump a switch and tend to follow a siding while the train is traveling on a main line, the abnormal turning 45 movement of the truck will result in the turning of one or other of the cam plates 61 into engagement with the link, and as these cam plates cannot pass through the links they must move the latter either up or down 50 and movement in either direction will result in opening movement of the valve. Any abnormal rocking movement of the car will bring the link into engagement with the relatively stationary cam bar and result in movement 55 of the stem and rock shaft, so that un-

der practically all conditions the car is safeguarded and an emergency application of the brakes will result in case of danger.

In hopper gondolas and other forms of hopper cars, there is but little if any room below 70 the car platform, and in such cases it may be desirable to place the valve at a point above the car platform and under the hopper. This arrangement is shown in Fig. 2.

The rock shafts are formed in sections, the 75 sections 38^a which extend from the valve being provided with crank arms 70 and the sections 38^b that extend from the truck actuated mechanisms being provided with crank arms 71. The cranks are connected by suitable rods or links 72 for the purpose of transmitting the movement. This merely illustrates one method of arranging the valve at a point other than in a direct line from the truck actuated mechanisms. 80 85

I claim:

1. In apparatus of the class described, a single train pipe opening valve, and a pair of independently operable truck actuated mechanisms, each including a valve engaging member arranged to move the valve to open position independent of the other member. 90

2. In apparatus of the class described, a single train pipe opening valve arranged on each car, a valve actuated mechanism arranged on each truck, and independent connections between the actuating mechanisms and the valve, and each of said connections including a valve engaging member arranged to engage and open the valve independent of 95 the other member. 100

3. In apparatus of the class described, a single train pipe opening valve on each car, independently movable valve operating devices carried by each truck, and operating 105 connections extending from said operating devices to the valve and including valve engaging cams arranged to operate independent of each other.

4. In apparatus of the class described, a 110 train pipe opening valve, a pair of valve operating mechanisms arranged one on each truck, rock shafts extending from the operating mechanism to the valve, and means on said rock shaft for moving the valve to open 115 position.

5. In apparatus of the class described, a train pipe opening valve, a pair of relatively 120 movable actuating devices arranged at each truck, rock shafts extending from said actuating devices to the valve, and independent cams carried by the rock shafts and arranged to open said valve.

6. In apparatus of the class described, a valve casing connected to the train pipe, a 125 spring closed valve in said casing, a disk connected to the valve, a rock shaft, a cam disposed on the rock shaft and arranged to engage the disk, and a truck actuated device for imparting movement to the rock shaft. 130

7. In apparatus of the class described, a valve casing connected to the train pipe, a spring closed valve in said casing, a disk secured to the valve, a rock shaft journaled in the casing, a double cam carried by the rock shaft and engaging the disk, and a truck actuated member for imparting movement to said rock shaft.

8. In apparatus of the class described, a valve casing connected to the train pipe, a valve seat plug arranged therein and provided with a central passage, and a valve seat, a valve arranged to close against the seat, said valve being subjected to the train pipe pressure, a stem carrying the valve, a disk secured to the stem, a rock shaft journaled in the casing, a cam carried by the rock shaft and arranged to engage the disk, and a truck actuated mechanism for imparting movement to said rock shaft.

9. In apparatus of the class described, a casing connected to the train pipe, a valve

seat plug arranged therein and provided with a central passage, and a valve seat, said plug being further provided with exhaust ports 25 leading to the passage, and the casing having ports alining with said exhaust ports, a valve arranged to close against the seat and subjected to the train pipe pressure, a stem carrying the valve, a disk secured to the 30 stem, a spring engaging said disk and tending to move the valve to closed position, a rock shaft journaled in the casing, a double cam carried by the rock shaft and provided with removable wear pins, and a truck actuated 35 means for operating said rock shaft.

In testimony that I claim the foregoing as my own, I have hereto affixed my signature in the presence of two witnesses.

JOHN BUNYAN WRIGHT.
